UNITED STATES PATENT OFFICE.

GARDNER C. KAVANAGH AND WILLIAM GEORGE WINTERBOTHAM, OF ROCHESTER,
NEW YORK, ASSIGNORS TO AMERICAN PIANO COMPANY, OF NEW YORK, N. Y., A CORPORATION OF NEW JERSEY.

DESIGN FOR A PIANO-CASE.

48,728.

Specification for Design.

Patented Mar. 14, 1916.

Application filed January 11, 1916. Serial No. 71,591. Term of patent 7 years.

To all whom it may concern:

Be it known that we, GARDNER C. KAVANAGH, a citizen of the United States, and WILLIAM GEORGE WINTERBOTHAM, a subject of the King of Great Britain, both residing in the city of Rochester, in the county of Monroe and State of New York, have invented a new, original, and ornamental Design for a Piano-Case, of which the following description, in connection with the accompanying drawing, is a specification.

The single figure of the drawing is a perspective view of a piano case showing our new design.

We claim:

The ornamental design for a piano case, as shown.

In witness whereof we have signed our names to this specification this 7th day of January, 1916.

GARDNER C. KAVANAGH.

WILLIAM GEORGE WINTERBOTHAM.
